DESIGN FOR A SAFETY-RAZOR BLADE

Secondin Massard, New York, N. Y.

Application July 3, 1940, Serial No. 93,413

Term of patent 7 years

To all whom it may concern:

Be it known that I, Secondin Massard, a citizen of the United States, residing at 258 Riverside Drive, New York city, in the county of New York and State of New York, have invented a new, original, and ornamental Design for a Safety-Razor Blade, of which the following is a specification, reference being made to the accompanying drawing, forming part thereof.

Fig. 1 is a plan view of a safety-razor blade showing my new design; and

Fig. 2 is an end view.

I claim:

The ornamental design for a safety-razor blade, substantially as shown.

SECONDIN MASSARD.
